UNITED STATES PATENT OFFICE

149,710

DESIGN FOR A CHILD'S SEATING AND
MOVING AIRPLANE TOY

Cecil J. Van Valkenburgh, Belleville, Mich.

Application March 29, 1946, Serial No. 128,062

Term of patent 14 years

(Cl. D34—15)

To all whom it may concern:

Be it known that I, Cecil J. Van Valkenburgh, a citizen of the United States, residing at Belleville, in the county of Wayne and State of Michigan, have invented a new, original, and ornamental Design for a Child's Seating and Moving Airplane Toy, of which the following is a specification, reference being had to the accompanying drawings, forming a part thereof, and in which:

Figure 1 is a view in side elevation of a child's seating and moving airplane toy, showing my new design.

Fig. 2 is a view in front elevation.

Fig. 3 is a top plan view.

I claim:

The ornamental design for a child's seating and moving airplane toy, substantially as shown.

CECIL J. VAN VALKENBURGH.
